UNITED STATES PATENT OFFICE

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

RAILWAY DRAFT APPLIANCE

Application filed February 14, 1928. Serial No. 254,287.

My invention relates to railway draft appliances, and particularly to means for mounting upon freight cars and tenders longitudinally movable couplers which are 5 formed with enlarged butts.

The principal object of the invention is to provide means for effectively supporting a spring-cushioned coupler of the character indicated in a manner such that it may be 10 readily removed whenever replacement becomes necessary.

Where freight cars and locomotive tenders are provided with couplers associated with spring-cushion mechanism allowing the 15 couplers to reciprocate, it is the common practice to locate the coupler carrier to the rear of the coupler head a distance sufficient to afford the clearance required to enable the coupler to move rearwardly the full amount 20 of the normal travel of the draft gear, plus an allowance for wear. As this location of the carrier is considerably to the rear of the center of gravity of the coupler, the latter naturally tends to droop at the head end and, 25 consequently, as the means provided for attaching the coupler to the draft gear wear this droop increases in extent.

To provide for the proper operation of couplers in the act of coupling, and also to 30 afford requisite flexibility for vertical and horizontal angling, couplers are formed with contours providing horizontal clearance between opposing couplers when the latter are in coupled relation. If the couplers are allowed to droop this clearance is in effect reduced and the flexibility between adjacent 35 couplers is reduced accordingly. If permitted to become excessive drooping also seriously affects the operation of the couplers 40 in the act of coupling, so that, in order to insure proper and efficient operation, it is important to maintain the couplers horizontal. It is also desirable that this result should be attained by means permitting the 45 couplers to be readily removed and replaced in the event of breakage and it is likewise advantageous that the means provided for the purpose shall be of a nature permitting 50 couplers of standard form to be employed for purposes of repair as delays arising from in-

ability to obtain special parts are thereby avoided.

Generally stated, the principal feature of the invention consists in securing to a freight car or locomotive tender a coupler mounting 55 formed with an opening for receiving the shank of a car coupler and permitting it to reciprocate in draft and buffing therethrough, the opening being of a size and form enabling the coupling to be withdrawn when it is disconnected from the draft gear and the mounting being provided with a carrier adapted to 60 slidably engage the under surface of the coupler head so as to support the coupler in horizontal position during its reciprocating movements.

Another feature of the invention consists in so forming the coupler mounting that is secured to the freight car or locomotive tender 65 that the opening thereof for receiving the shank of the car coupler is adapted to permit the insertion and withdrawal of a coupler having an enlarged butt; means being provided for slidably engaging the under surface of the coupler head so as to support the coupler in horizontal position during draft and buffing movements, and provision being 70 made whereby a carrier located in the usual position may be employed if desired in case the special form of coupler is not immediately 75 available for repairs.

Other features of the invention pertaining to particular combinations and advantageous 80 details of construction will hereinafter appear and be pointed out in the claims.

In the drawings illustrating preferred 85 embodiments of the invention,

Figure 1 is a plan view of a draft appliance embodying the invention, shown as applied to a locomotive tender frame, the car coupler being of the pivoted type and provided with an enlarged butt enabling it to have a quadruple shear connection with the draft yoke;

Fig. 2 is a view, partly in side elevation and partly in vertical section, of the construction shown in Fig. 1;

Fig. 3 is a detail elevational view of the 100 central portion of the tender frame, the rela-

tive position of the shank of the car coupler being indicated in dot and dash lines;

Fig. 4 is a fragmentary plan view of the structure shown in Fig. 3;

Fig. 5 is a view, partly in plan and partly in horizontal section, showing the invention as applied to a striking casting, the butt of the coupler being formed with liner blocks;

Fig. 6 is a view illustrating the construction shown in Fig. 5, the striking casting being in vertical central section and the car coupler being in side elevation;

Fig. 7 is a detailed sectional view illustrating a modification of the coupler carrier portion of the striking casting shown in Figs. 5 and 6;

Fig. 18 is a detailed view showing in vertical central section a modified form of the coupler supporting portion of the tender frame illustrated in Fig. 1;

Fig. 19 is a front elevational view of the construction in Fig. 18, a carrier iron in the usual position being shown as assembled therewith;

Fig. 20 is a section on the line 20—20, Fig. 19;

Fig. 21 is a detail view, partly in section and partly in front elevation, showing a modified form of the coupler carrier portion of the striking casting illustrated in Figs. 5 and 6;

Fig. 22 is a sectional view on the line 22—22, Fig. 21;

Fig. 23 is a view corresponding to Fig. 22, but illustrating the use of a bar forming a coupler carrier located in the usual position;

Fig. 24 is a front elevational view of a striking casting having detachably connect-

ed thereto a carrier adapted to support a reciprocating coupler by engaging the under side of the coupler head;

Fig. 25 is a sectional view on the line 25—25, Fig. 24;

Fig. 26 is a plan view of the construction shown in Fig. 24;

Fig. 27 is a view corresponding to Fig. 25, but showing a common form of coupler carrier associated with a striking plate in substitution for the special carrier;

Fig. 28 is a plan view of a portion of another form of tender frame casting showing the invention applied thereto;

Fig. 29 is a section on the line 29—29, Fig. 28;

Fig. 30 is a front elevation of the construction shown in Fig. 28, the position of the coupler shank being indicated by dot and dash lines;

Fig. 31 is a view, partly in plan and partly in horizontal section showing a coupler with an enlarged end associated with a striking casting of substantially the same form as that shown in Fig. 5, the rear end of the coupler being adapted for quadruple shear connection with the draft yoke;

Fig. 32 is a view, partly in vertical section and partly in side elevation, of the construction shown in Fig. 31;

Fig. 33 is a front elevational view of the tender frame casting illustrated in Figs. 31 and 32, the position of the coupler shank with respect thereto being shown in dot and dash lines;

Fig. 34 is a sectional view on the line 34—34, Fig. 32.

The construction illustrated in Figs. 1 to 4 inclusive represents the application of my invention to a large combination casting forming an under-frame, the particular casting illustrated being a frame for a locomotive tender. Except as otherwise indicated, this tender frame casting 1 may be made of any form required to embody in it the necessary detail parts, the form here illustrated being one which is in use to a considerable extent at the present time. It is provided with rearwardly extending spaced draft arms 2, affording stops 3 for the forward draft gear follower (not shown). At its outer end it is fashioned with an opening 4 through

which the shank 5 of the car coupler 6 extends, the opening being of sufficient size to permit the enlarged rear end 7 of the coupler to pass therethrough. As shown, the coupler butt 7 is in the form of spaced pivot lugs for receiving a tail pin 8 to form a pivotal connection with the draft yoke 9, the tail pin being in quadruple shear.

The opening 4 in the casting 1 is of sufficient width to permit the coupler to have the desired range of lateral swinging movement. It is preferably closed at the bottom by a cross tie 10 which projects forwardly so as

to extend under the head of the coupler in all positions of draft and buffing the latter may assume in service, its outer end thereby affording a coupler carrier 11 integrally united to the casting 1.

Instead of having the coupler carrier 11 support the coupler by bearing directly against the coupler head it is preferred to employ a wear shoe 12 which in effect forms part of the carrier and may be of the well known channeled form having downwardly extending flanges. To permit the shoe 12 to be brought into assembled relation with the coupler carrier 11, a suitable slot 13 is provided in the cross tie immediately to the rear of the carrier.

In order that the coupler head may be slidably supported on the shoe 12 of the carrier so as to be capable of reciprocating in draft and buffing, the under side of the coupler head is formed with a flat bearing surface or pad 14 which preferably lies in a horizontal plane meeting the striking face of the coupler at the lowest point of the latter. The bearing face or pad 14 should not be located above the lower part of the striking face of the coupler because such location would not afford sufficient clearance for the carrier to permit the coupler to execute full draft and buffing movement.

The striking casting 15, shown in Figures 5 and 6, is designed for cooperation with a car coupler 16 whose shank 17 is formed at the rear end with liner blocks 18. The special form of casting shown provides spaced draft arms 19 affording follower stops 20 for the forward follower of the draft gear (not shown). At its forward end the casting 15 is formed with an opening 21 through which the shank of the coupler extends and through which its enlarged butt may pass. A cross tie 22 formed integral with the casting and serving to close the bottom of the opening 21 projects forwardly so as to provide a coupler carrier 23 extending beneath the coupler head. As in the construction heretofore described, the coupler head is formed on its under side with a horizontal seat or pad 14 adapted to be slidably supported upon the wear shoe 12 mounted on the carrier. To permit the employment of the form of wear shoe 12 commonly used and therefore readily available for repairs, the cross tie 22 of the striking casting has a transversely extending slot 24 for receiving the inner depending flange of the shoe. If desired, however, a wear shoe 25 of sufficient width to extend longitudinally entirely across the upper surface of the cross tie may be employed as shown in Figure 7. In this latter construction the cross tie 26 need not be provided with a slot for receiving the inner flange of the wear shoe.

As it is desirable to be able to make repairs in an emergency by making use of the pres-

ent standard couplers, although the heads of the latter are unsuited for cooperation with a supporting carrier iron in the advanced position, it is advantageous to provide the striking casting with means enabling a separate carrier to be applied thereto in the present standard location. Means thus enabling such a separate carrier to be employed in an emergency are illustrated in Figures 8, 9 and 10 wherein inwardly projecting lugs 27 at the bottom of the opening for the coupler shank serve to support the ends of a transversely extending removable carrier 28 of the well known standard form illustrated in Figures 11 and 12. To receive the bolt 29 by which this carrier is maintained in assembled position the striking casting is provided with appropriate holes 30. The wear shoe 12 which normally is mounted upon the coupler carrier 31 integral with the striking casting may, as shown in Figure 10, be transferred to the removable carrier 28 when the latter is used in an emergency.

In the modified form of the invention illustrated in Figures 11 and 12 the lower portion of the striking casting is formed to receive a removable coupler carrier in either of two positions, one of those positions being such that the carrier extends beneath the coupler head associated therewith and the other being the usual location. For this purpose, and to permit a carrier 28 of well known form to be employed, the forwardly extending portions of the striking casting are provided on their inner sides at their outer ends with lugs or shoulders 32 corresponding in function to the lugs 27 disclosed in Figures 8, 9 and 10. These lugs support the coupler carrier 28 in its advanced position. Similar lugs 33, at a higher elevation and to the rear, likewise serve to support the carrier when the latter is transferred in position so as to enable it to support the present standard coupler in case of an emergency. In either position the coupler carrier is retained in assembled relation to the striking casting by means of a transversely extending bolt 34 passing through suitable apertures 35 arranged opposite each other in pairs. The usual wear shoe 12 is designed to be mounted upon the upper side of the coupler carrier. The striking casting 36 illustrated in these views may otherwise correspond in construction to the striking casting 15 of Figures 5 and 6.

Another advantageous manner of supporting the well known form of coupler carrier 28 upon the striking casting so that it may occupy a position beneath the coupler head or beneath the coupler shank, as occasion may require, is shown in Figures 13 and 14. The striking casting 37 illustrated in these figures is of the same general form as that shown in Figures 5 and 6, except that lugs 38 and bolt holes 39, corresponding respec-

5 tively with lugs 33 and openings 35 here-
10 tofore described, are provided for supporting
the carrier in its upper and rearward loca-
tion, and except also that the forwardly ex-
tending lower portion of the striking casting
15 is fashioned with a channeled cross bar
20 40 providing a recess for receiving a carrier
28. The ends of the carrier rest upon shoul-
ders 41 adjacent the ends of the cross tie
25 40 and a wear shoe 12, which is adapted to en-
gage the pad or bearing surface 14 on the
under side of the coupler head (see Figs. 1
30 and 2), is mounted upon the carrier in the
usual manner.

15 Figures 15, 16 and 17 disclose the invention
as embodied in a striking casting unprovided
with draft arms. This casting 42 is formed
20 with a marginal flange or base plate 43 where-
by it may be secured to the car structure
25 and has upon its front face a projection 44
against which the coupler may strike. The
opening 45 therein, through which the shank
30 of the coupler projects, is sufficiently high to
permit a coupler having an enlarged butt to
be inserted and withdrawn. The opening 45
35 is closed at the bottom by a cross tie 46 which
extends forwardly and is formed at its outer
end to provide a coupler carrier 47 adapted
to stand beneath the coupler head. The rigid
40 portion 47 of the carrier is preferably of a
form adapting it to be associated with the
well known type of wear shoe 12. With the
exception of the wear shoe all the parts are
45 formed as an integral casting.

50 35 The construction shown in Figures 18, 19
and 20 is a modification of that shown in
Figures 1 to 4 inclusive. In this modifica-
55 tion the lower portion of the striking casting
48 is provided with means for permitting
a removable coupler carrier 49 to be mounted
60 thereon in a position permitting it to engage
and support the shank of the present stand-
ard coupler. The means shown for this pur-
pose consist of inwardly projecting shelves
65 or lugs 50 having suitable holes for receiving
the bolts 51 by which the carrier is retained
in assembled position. It is to be understood,
70 of course, that the carrier 49 is not to be used
in case a coupler having a suitable bearing
75 surface on its under side such, for example,
as the seat or pad 14, is available. For the
purpose of cooperating with a coupler pro-
vided with the necessary bearing surface on
80 its under side the striking casting is fashioned
at its lower end with the carrier 52. This
carrier which is in the advanced position is
85 preferably protected from wear by a shoe 12
extending transversely the full length of the
90 carrier 52. Other details of construction of
the striking casting 48 may correspond to
those disclosed in Figures 1 to 4 inclusive.
95 The opening 53, through which the coupler
extends, is of sufficient size to permit a cou-
pler having an enlarged butt to be inserted

100 and withdrawn when the removable carrier
49 is not in place.

105 Figures 21, 22 and 23 illustrate a modifica-
tion of the striking casting of Figures 5 and
6, whereby means are provided to permit a
110 standard coupler to be employed in case an
emergency makes it necessary. In this form
115 of the invention a striking casting 54 is pro-
vided at opposite sides of the coupler open-
120 ing 55 with horizontally aligned openings 56,
125 preferably of rectangular form, to receive a
transversely extending bar 57 of correspond-
ing cross section. When in position this bar
130 is adapted to engage the under surface of the
shank of a standard coupler so as to form a
carrier therefor. It is retained in position
135 by bolts 58 extending through perforated
lugs 59 on the outer faces of the striking cast-
ing adjacent the corresponding openings 56.
140 The opening 55 is of sufficient size to permit
145 a coupler having an enlarged butt to be as-
sembled and disassembled as has heretofore
been explained. In other respects, the struc-
150 tural features of the striking casting 54 cor-
respond in form and function with similar
155 parts of the striking casting 15 heretofore
described and accordingly similar features of
construction have been identified by corre-
160 sponding reference numerals. Figures 24,
25 and 26 show a well known form of striking
165 casting 60 equipped with a coupler carrier
member embodying the invention. In this
170 form of the device, the lower end of the cou-
pler receiving opening 61 is closed by yoke
175 or cross tie member 62 rigidly secured to
the striking casting 60 by bolts 63, the por-
180 tion of the cross tie which is below the open-
ing 61 being recessed or depressed suffi-
185 ciently to permit a coupler having an enlarged butt,
such as that shown in Figures 5 and 6, to
190 pass. The lower portion of the member 62
projects forwardly and is fashioned at its
195 outer end with a coupler carrier member 64
integral therewith. The carrier is preferably
200 protected from wear, due to the reciprocat-
ing movements of the coupler beneath the
205 head of which it extends, by being provided
with the usual carrier wear shoe 12. As
210 shown in Figure 27 the yoke 62 may be
215 removed and a carrier 65 substituted there-
220 for, the latter being in the usual position per-
225 mitting it to cooperate with and support the
230 shank of the usual standard coupler.

235 Figures 28, 29 and 30 illustrate a form of
the invention showing a carrier providing
240 forward support for the coupler and which
is so designed that it may be substituted for
the usual carrier without any change in
striking casting or other parts of the car.
245 The striking casting here illustrated is in the
form of a locomotive tender frame casting
250 66 in common use. In place of the usual car-
rier there is associated with the tender cast-
ing a special carrier member 67, bolts 68
255 being employed to form a rigid connection

between these parts. The upper surface of the member 67 which spans the space between the draft arms 69 is depressed at the center, as at 70, to provide clearance permitting the insertion and withdrawal of a coupler having an enlarged butt, this construction being particularly suitable for couplers whose butts are designed to be connected to the draft yoke in quadruple shear. The member 67 extends 10 forwardly to provide a coupler carrier member 71 positioned beneath and adapted to support the head of the car coupler. The carrier 71 may be protected from wear by means of its usual shoe 12.

15 Figures 31 to 34 inclusive show an adaptation of a striking casting such as that illustrated in Figures 5 and 6 suitable for use with a coupler having an enlarged end of the character necessary for quadruple shear connection to the draft yoke, the casting being so proportioned that the distance from the back of the striking bracket 72 of the coupler to the front face of the front follower is the same as in the present standard freight 20 coupler. This striking casting 73 differs from the casting 15 heretofore described in that the reinforcing web 74, upon its interior, is somewhat shortened to afford necessary clearance for the enlarged butt 75 and draft 25 yoke 76.

It will be appreciated that the invention 30 permits the use of couplers having enlarged rear ends of the liner block type, thus gaining the advantage of providing a greater surface 35 face of the coupler in contact with the follower or other cooperating part of the draft gear and thereby minimizing the upsetting or wear that occurs between those contacting parts as a result of service. It will also be appreciated that by causing the coupler carrier 40 to cooperate with the head of the reciprocating coupler it becomes possible to design striking castings, and particularly large combination castings, affording much more space 45 for quadruple shear or other comparatively large forms of connection of the rear of the coupler shank to the draft yoke, because the obstruction resulting from the present location of the carrier is avoided and the upper 50 portion of the casting can be shaped to suit conditions and provide the necessary strength. With the present location of carrier, when used in connection with couplers having short shanks such as the present 55 standard length of freight couplers, this is not possible. While the drawings illustrate embodiments of the invention in forms suitable for application to many locomotive tenders and freight cars now in use, it is to 60 be understood that the invention is not limited to the particular details of construction shown in the drawings.

I claim:

1. In a railway draft appliance, the combination with a car coupler having a head and

shank, of means for mounting the coupler on a railway vehicle so as to permit it to reciprocate in draft and buffering in opposite directions from normal position, said means being formed with a wall extending under said shank and spaced downwardly with respect thereto and including a coupler carrier extending under and supporting said head and adapted to slidably cooperate therewith, and the under surface of the head being formed with a seat for cooperating with said carrier, said seat being at an elevation not substantially greater than that of the lowest point of the forward face of the coupler head. 70

2. In a railway draft appliance, the combination with a car coupler having a head and a shank formed with a vertically enlarged butt adapted to be connected to yoke acting means, of means for mounting the coupler on a railway vehicle so as to permit it to reciprocate in draft and buffering in opposite directions from normal position, said means being formed with an opening for receiving said shank and through which said enlarged butt is adapted to pass and including a coupler carrier extending under and supporting said head and adapted to slidably cooperate therewith, said carrier being spaced downwardly with respect to said enlarged butt. 80

3. In a railway draft appliance, the combination with a car coupler having a head and a shank formed with a vertically enlarged butt, of means for mounting the coupler on a railway vehicle so as to permit it to reciprocate in draft and buffering in opposite directions from normal position, said means including a member having an opening therethrough permitting the passage of said enlarged butt, and including a coupler carrier extending under and supporting said head and adapted to slidably cooperate therewith, the lower wall of said opening being spaced downwardly with respect to said enlarged butt and being disposed rearwardly of said carrier. 90

4. In a railway draft appliance, the combination with a car coupler having a head and a shank provided at its rear end with means for connecting it to a draft yoke, of means for mounting the coupler on a railway vehicle so as to permit it to reciprocate in draft and buffering in opposite directions from normal position, said means including a member formed with an opening through which said shank extends and provided with a coupler carrier extending under and supporting said head and adapted to slidably cooperate therewith, said head having upon its under surface a seat for cooperating with the carrier, said seat being in a horizontal plane at least as low as the lowest point of the striking face of the coupler, and said opening being closed at its lower end by a wall forming an integral part of said mem- 100
105
110
115
120
125
130

ber and extending under said shank in spaced relation thereto.

5. In a railway draft appliance, the combination with a car coupler having a head and a shank formed with a vertically enlarged butt, said coupler being adapted to be connected to a draft yoke, of means for mounting the coupler on a railway vehicle so as to permit it to reciprocate in draft and buffering in opposite directions from normal position, said means including a member provided with a coupler carrier extending under and supporting said head, and said member having an opening therethrough permitting the passage of said enlarged butt, the lower wall of said opening forming an integral part of said member and being spaced downwardly from the lower side of said enlarged butt.

20. 6. In a railway draft appliance, the combination with a car coupler having a head and a shank formed with a vertically enlarged butt, of means for mounting said coupler on a railway vehicle so as to permit it to reciprocate in draft and buffering in opposite directions from normal position, said means including coupler supporting means mounted on the car and having an opening permitting the passage of said butt, said coupler head being provided on its under side at a point spaced downwardly with respect to the under surface of said enlarged butt with a seat adapted to slidably engage the coupler supporting means, and the under side of said enlarged butt being spaced upwardly with respect to the bottom wall of said opening.

40. 7. In a railway draft appliance, the combination with a car coupler having a head and a shank formed with a vertically enlarged butt of means for mounting the coupler on a railway vehicle so as to permit it to reciprocate in draft and buffering in opposite directions from normal position, said means being formed with an opening having upper and lower walls between which the shank extends and through which said enlarged butt is adapted to pass and including coupler carrier means extending under and supporting the head, said lower wall and said carrier means being spaced downwardly with respect to the lower side of said enlarged butt.

45. 8. In a railway draft appliance, the combination with a car coupler having a head and a shank formed with a vertically enlarged butt adapted to be connected to a draft yoke, of means for mounting the coupler on a railway vehicle so as to permit it to reciprocate in draft and buffering in opposite directions from normal position, said means involving a frame provided with an opening having upper and lower walls spaced from said shank and between which said butt is adapted to pass, said lower wall being spaced downwardly with respect to the lower side of said

butt, and coupler carrier means engaging the coupler at a point below the under surface of the enlarged butt.

9. In a railway draft appliance, the combination with a car coupler having a head and a shank formed with a vertically enlarged butt, of means for mounting the coupler on a railway vehicle so as to permit it to reciprocate in draft and buffering in opposite directions from normal position, said means including a frame rigidly mounted on the car and provided with integrally connected upper and lower cross ties upon opposite sides of said shank and between which said butt is adapted to pass and having a forwardly projecting portion extending under the coupler head to form a coupler carrier cooperating with said head, said lower cross tie being spaced downwardly with respect to the under side of said shank and with respect to the under side of said butt.

In testimony wherof I affix my signature.
